Modern Packaging, Jul. 1978, p. 30, "Pepsi" bottle, far right.

Primary Examiner—Lucy Lieberman
Attorney, Agent, or Firm—Finnegan, Henderson, Farabow, Garrett & Dunner, L.L.P.[57] **CLAIM**

The ornamental design for a bottle, as shown and described.

DESCRIPTION

FIG. 1 is a front elevation of a bottle showing our new design, the appearance repeats five times around the axis of the bottle;

FIG. 2 is a top plan view thereof;

FIG. 3 is a bottom plan view thereof; and,

FIG. 4 is a cross-sectional view thereof, taken along line 4—4 shown in FIG. 1.

The broken lines shown in FIGS. 1-3 form no part of the claimed design.
